J. d. Chapman

United States Patent Office.

GEORGE HENSLER, OF KANKAKEE, ILLINOIS.

Letters Patent No. 96,109, dated October 26, 1869.

IMPROVEMENT IN LIME-KILNS.

The Schedule referred to in these Letters Patent and making part of the same.

To all whom it may concern:

Be it known that I, GEORGE HENSLER, of Kankakee, in the county of Kankakee, and State of Illinois, have invented an Improved Lime-Kiln; and I do hereby declare that the following is a full, clear, and exact description thereof, which will enable those skilled in the art to make and use the same, reference being had to the accompanying drawings and letters marked thereon, making a part of this description, in which—

Figure 1 is a vertical section, taken on the line *x*, fig. 3.

Figure 2, a vertical section, taken on line *Z*, fig. 3.

Figure 3, a horizontal section, taken on the line *Y*, figs. 2 and 3.

Figure 4, a perspective representation of the valve and its gearing removed from the kiln.

The nature of the present invention consists in the novel construction of the cupola, in combination with a series of chambers for retaining the heat in the same, and the novel construction and arrangement of a dumping-valve, whereby burned lime may be drawn off at the bottom of the kiln, without disturbing the fires, or interfering with the continuous process of burning, as the whole is hereinafter fully described.

A represents the ordinary masonry-work of a lime-kiln, the inside of which has my improved construction, as follows:

The upper part *D* of the cupola nearly corresponds to the shape of an inverted truncated cone, the smaller end of which fits closely to a chamber, *C*, whose base fits on to a hopper, *F*, which is provided with an opening, *G*, for drawing the burned lime off.

The object of making the cupola in this manner is to hold the limestone up in the cupola, while the lime which is burned is being removed, the smaller part of the cupola, at *E*, figs. 1 and 2, accomplishing this purpose.

A chamber, *B*, is formed in the under part of the

kiln, for the convenience of placing a cart or car under the cupola to receive the lime.

The means for dumping the lime into the cart consists of a rotating valve, *J H N*, which has a round side, *J*, fitted to turn against the concave stone-work of the lower part of the neck *G*, and which is hung on a shaft, *K*, having bearings in the sides of chamber *B*.

This shaft *K* has fastened to one end a pinion, *b*, which is so operated upon by a ratchet, *d*, and lever, *e*, as to bring the flat side *N*, fig. 5, of the valve opposite to the hole in the neck *G*, and consequently allow lime to pass out of chamber *C*.

The fire-boxes are shown at *M* and the ash-boxes at *L*, the device for dumping the grate consisting of a crank-lever, *R*, fig. 1.

The parts are shown at *f f*, fig. 4, any required number of them being used.

The means for retaining the heat in the chamber *G* consists of a series of smaller chambers, *I I I*, &c., made in its sides, as shown at figs. 1 and 2, whereby the heat from the fire-boxes is prevented from escaping too rapidly; consequently a considerable saving of fuel is made.

The kiln, as constructed, is intended to burn lime continuously without putting out the fires, as is now done when lime is burned in the ordinary kiln.

By this means, I expect to save the cost of making a new fire at each charge, and also much delay.

Having thus described my invention,

What I claim, and desire to secure by Letters Patent of the United States, is—

The rotating valve *J N*, operated by pinion *b* and ratchet-lever *d e*, in combination with chamber *B*, cupola *D G F-G*, and kiln, as described.

GEORGE HENSLER.
